UNITED STATES PATENT OFFICE.

FRANK HEESH, OF LAKE COMO, PENNSYLVANIA.

MATCH-BOX.

1,221,732.

Specification of Letters Patent.

Patented Apr. 3, 1917.

Application filed July 19, 1916. Serial No. 110,220.

To all whom it may concern:

Be it known that I, FRANK HEESH, a citizen of the United States of America, residing at Lake Como, in the county of Wayne 5 and State of Pennsylvania, have invented certain useful Improvements in Match-Boxes, of which the following is a specification, reference being had therein to the accompanying drawing.

10 This invention relates to improvements in match boxes, one object of the invention being the provision of a match box in which mechanism is provided for delivering one match at a time, and by means of which the 15 matches are stored in a safe condition when not in use.

A further object of this invention is the provision of a device of this character which is simple, durable and inexpensive in construction and thoroughly efficient and practical in use.

In the accompanying drawings;

Figure 1 is a front elevation of the complete match box, made according to and embodying the present invention.

Fig. 2 is a cross section taken on line 2—2 thereof.

Fig. 3 is a section taken on line 3—3 of Fig. 1.

30 Referring to the drawings, the numeral 5 designates a casing having a transverse partition 6 dividing the same into two compartments 7 and 8, one of said compartments being provided with an outlet opening 9, while the other is provided with an outlet 10 at the opposite end of the box.

Mounted in each compartment adjacent the outlet opening thereof is a roller or shaft 11 having the operating knob 12 exteriorly thereof, while adapted to be wound upon said roller within the compartment is a flexible strip 14 of any desired material, the opposite end thereof being attached to the bar 14, having the central notch or recess 15 to permit of the bar to be guided on the longitudinally arranged strip 15' carried by the wall of the casing. The bar is of sufficient size to substantially fill the compartment so that the matches 16 will be disposed therein in a single layer and spaced

from the wall of the casing by the strip 15' to prevent accidental ignition of the matches while they are being withdrawn, the innermost notch abutting the bar and coöperating therewith to assist when the roller is rotated to wind thereon the flexible material and feed one match at a time to its respective outer opening.

Disposed adjacent to each of the respective outer openings is a metal strip 17 which is provided with the inwardly projecting lug or projection 18 for disposition in the path of the matches, the same being a resilient member so as to normally hold the matches from accidental spilling, but not interfering with the feed thereof when its respective roller is operated.

It will thus be seen that both of the rollers are operable from the same end of the box or case, while upon the opposite end is provided the striker 19. In this form of match box or safe, it is apparent that the matches are kept in a safe condition and are only fed therefrom one at a time as desired.

What I claim as new is:—

1. A match box including a casing having an outlet opening adjacent one end thereof, a match feeding bar mounted in the casing, a flexible strip connected to the bar, means for operating the strip to move the bar and feed and deliver matches through the outlet opening, means for guiding the match feeding bar and for spacing the heads of the matches from the wall of the casing to prevent accidental ignition thereof during the actuation of the operating means, and means for retarding matches mounted adjacent the opening.

2. A match box including a casing having an outlet opening adjacent one end thereof, a match feeding bar mounted in the casing and provided with a groove, a flexible strip connected to the feeding bar for receiving a single layer of matches, a roller operatively mounted in the casing adjacent the outlet opening and having the flexible strip connected thereto and windable thereabout to consequently actuate the feed bar so as to deliver matches from the opening, a strip mounted longitudinally of the inner surface

of one wall of the casing and engageable by the groove in the match feeding bar for guiding the bar during movement and arranged for spacing matches from the wall of the casing to prevent accidental ignition thereof during the operation of the roller, and a resilient match retarding member

mounted adjacent the outlet opening for allowing only one match to be delivered at a time.

10

In testimony whereof I affix my signature.

MR. FRANK HEESH.
